(57) CLAIM

The ornamental design for an undergarment, as shown and described.

DESCRIPTION

FIG. 1 is a front view of an undergarment, as worn by a person (the person not forming part of the design).

FIG. 2 is a rear view of the undergarment of FIG. 1, as worn by a person (the person not forming part of the design).

FIG. 3 is a top view of the undergarment of FIG. 1.

FIG. 4 is a bottom view of the undergarment of FIG. 1.

FIG. 5 is a side view of the undergarment of FIG. 1, as worn by a male person (the person not forming part of the design).

FIG. 6 is a further side view of the undergarment of FIG. 1, as worn by a male person (the person not forming part of the design).

FIG. 7 is a side view of the undergarment of FIG. 1, as worn by a female person (the person not forming part of the design).

FIG. 8 is a further side view of the undergarment of FIG. 1, as worn by a female person (the person not forming part of the design).

FIG. 9 is a front view of a further undergarment embodiment, as worn by a person (the person not forming part of the design).

FIG. 10 is a rear view of the undergarment of FIG. 9, as worn by a person (the person not forming part of the design).

FIG. 11 is a top view of the undergarment of FIG. 9.

FIG. 12 is a bottom view of the undergarment of FIG. 9.

FIG. 13 is a side view of the undergarment of FIG. 9, as worn by a male person (the person not forming part of the design).

FIG. 14 is a further side view of the undergarment of FIG. 9, as worn by a male person (the person not forming part of the design).

FIG. 15 is a side view of the undergarment of FIG. 9, as worn by a female person (the person not forming part of the design); and,

FIG. 16 is a further side view of the undergarment of FIG. 9, as worn by a female person (the person not forming part of the design).

The broken line showing of the person is for illustrative purposes only and forms no part of the claimed design.
